UNITED STATES PATENT OFFICE.

GEORGE FRANCIS, OF COLUMBUS, OHIO.

DESIGN FOR AN INK-WELL.

SPECIFICATION forming part of Design No. 29,362, dated September 20, 1898.

Application filed April 18, 1898. Serial No. 678,017. Term of patent 7 years.

To all whom it may concern:

Be it known that I, GEORGE FRANCIS, a citizen of the United States, residing at Columbus, in the county of Franklin and State of Ohio, have invented and produced a new and original Design for Ink-Wells; and I do hereby declare the following to be a full, clear, and exact description of the same, reference being had to the accompanying drawings, forming a part thereof.

In the said drawings, Figure 1 is a front view of an ink-well embodying my design. Fig. 2 is an edge view, and Fig. 3 is a rear view.
15 1 designates a representation of a well-curb formed of masonry, in the center of the upper portion of which is a circular opening. Over this is the representation of a windlass, 2 designating the upright portions thereof, 20 and 3 the drum or shaft, having at one of its ends the representation of a crank 4.
5 designates a representation of a rope hav-

ing one of its ends knotted in the drum or shaft and coiled about the shaft or drum, the other end of the rope extending to and being 25 connected with the representation of an "old oaken bucket" 6, resting at the side of the well-curb.

The frame at each side of the well is shown to be ornamented with vines. 30

The essential feature of my design is the well-curb with a surmounting windlass of substantially the shape and ornamentation shown in the accompanying illustration.

What I claim is—

The design of an ink-well substantially as shown and described.

In testimony whereof I affix my signature in presence of two witnesses.

GEORGE FRANCIS.

Witnesses:

I. M. FRANCIS,
GEORGE M. FINCKEL.
